UNITED STATES PATENT OFFICE.

GEORGE D. COX, OF LUKE, MARYLAND, ASSIGNOR OF ONE-HALF TO JOSEPH T. LAUGHLIN,
OF LUKE, MARYLAND.

SIGNAL FOR RAILWAYS.

No. 891,763.

Specification of Letters Patent.

Patented June 23, 1908.

Application filed February 11, 1908. Serial No. 415,391.

To all whom it may concern:

Be it known that I, GEORGE D. COX, a citizen of the United States, residing at Luke, in the county of Allegany and State of Maryland, have invented certain new and useful Improvements in Signals for Railways, of which the following is a specification.

This invention relates to station signals for railway trains.

10 The invention combines a visual signal provided with two arms one for "danger" and the other for "safety" and which normally will show the semaphore arm at the "danger" position, and will require the 15 station operator to manually hold the signal when the "safety" signal is to be exposed.

It also combines a shiftable rail on the track at the station which is mechanically connected with the mechanism that operates the semaphore arms, so that said rail will automatically be moved into its operative position simultaneously with the exposure of the "danger" signal, and manually moved out of its operative position simultaneously with the exposure of the "safety" signal.

20 The invention also combines means on the locomotive or tender for automatically venting the train-pipe of the air-brakes, to cause 25 the brakes to be applied in the event of the engineer running past the "danger" signal.

The invention also combines a lever and suitable mechanical connections whereby the said two signal arms, and the said shiftable rail may be simultaneously moved by the manual intervention of the operator, to the safety position, and which will remain in that position only while the operator holds it, and will automatically return to the danger position as soon as the operator releases his hold.

The invention is illustrated in the accompanying drawings, in which,—

Figure 1 is a plan view of the signal mechanism at the station. Fig. 2 is a side view showing the relative position of the railroad track, signal post, shiftable rail, and certain of the air-brake parts on a tender.

Fig. 3 is an elevation taken cross-wise of the railroad track, and showing the tender on the track, shiftable rail, signals, and mechanism in the signal tower. Fig. 4 shows a detail of the mechanism on the tender for venting the train-pipe of the air-brake.

55 A signal post, 1, supports two pivoted

semaphore arms, 2, and, 3, one for "danger" and the other for "safety" and the two arms are connected by mechanism which will always cause one or the other arm to be projected horizontally as a signal to the engineer of an approaching train. The two arms are shown on one and the same pivot shaft, 4, but at opposite sides of the post, 1, and their relative position with respect to each other is that of a right angle; thus when one arm has the horizontal or displayed position the other arm will have the pendent or vertical position, as indicated in Fig. 3.

The construction is such that normally the "danger" signal arm, 2, will be shown in the horizontal or displayed position by the action of the mechanism. The signal-tower is denoted by the wall, 5, and the floor, 6. Resting on this floor is the frame, 7, of the signal-lever, 8. This lever is kept normally in the danger position (shown in Fig. 3) by means of a spiral spring, 9, on the rod, 10, which is connected with said lever.

While the two signal arms, 2, and, 3, in the present instance are mounted on one pivoted-shaft, 4, such construction is not essential; the danger signal arm, 2, has a rod, 11, that connects with one end of a lever, 12, on the post and a rod, 13, attached at the other end of said lever connects with a lever-arm, 14, which is rigid on one end of a rock shaft, 15, that passes through the signal post, 1. The safety signal arm, 3, has a rod, 16, that connects with a lever-arm, 17, which is rigid on the other end of the rock-shaft, 15. This construction, it will be seen, so connects the two signal arms that when one arm is raised to the horizontal position the other arm will necessarily be lowered to the pendent position, indicated by broken lines in Fig. 3.

A shiftable rail, 18, rests upon the ends of the cross-ties parallel with the rails of the main track, and may be moved toward or away from said main track rails. When this rail, 18, is moved toward the main track rails it has its operative position, that is, the position where a roller, 19, on a locomotive or tender (in the present instance it is shown on a tender, 20,) will traverse said rail and by so doing will cause the air-brakes to be applied. Two or more short links, 21, are attached to the base-flange of the shiftable rail, 18, and project horizontally therefrom; and two or more bell-crank levers, 22, are

each secured by a pivot, 23, to a cross-tie, and one end of each of said levers connects with one of said links, 21. A rod, 24, parallel with the rail connects the other ends of all 5 of said bell-crank levers.

This invention has nothing to do with the construction or improvement of the well-known automatic air-brake. The tender, 20, will be supposed to be equipped with this 10 air-brake including the train-pipe, 25, which is always a part of such brake apparatus. The train-pipe is provided with an ordinary rotary plug-valve, 26, see Fig. 3, which is capable of making a quarter turn; when the 15 round plug is turned to one position, a passage diametrically through the round plug forms a continuous passage coincident with the passage in the said pipe, 25; this is the normal running position. The case that 20 incloses the round plug has a hole that opens to the atmosphere. When the round plug is given a quarter-turn so as to bring another passage in the plug into coincidence with the said hole in the case, then the compressed air 25 in the train-pipe will be vented to the atmosphere, and the reduction of pressure in the pipe thus produced will cause the brakes to apply.

The tender, 20, has at its bottom a down- 30 projecting pedestal, 27, provided with a vertical passage, 28; a shank or bar, 29, fits in this passage and is movable up and down therein and at its lower projecting end carries the roller, 19, hereinbefore named, 35 which traverses along the shiftable rail, 18. A spiral spring, 30, in the vertical passage, 28, presses the shank and roller downward, and the shank has teeth, 31; which forms a rack. A segment-shaped toothed quadrant, 40 32, is mounted on a rock-shaft, 33, one end of which is attached to the valve-plug, 26, of the air-brake pipe and the other end of which turns in the down-projecting pedestal, 27. The toothed quadrant, 32, engages with the 45 teeth, 31, of the shank. An arm, 34 (see Fig. 4) is on the rock-shaft and serves to turn the shaft and quadrant and thereby raise the shank, 29, and roller, 19, against the down-pressure of the spring, 30. A spring-bolt, 35, 50 is movable horizontally in the down-projecting pedestal, 27, and is pressed against the shank, and the shank, 29, has a notch, 36; when the shank and roller are raised by turning the arm, 34, the spring-bolt, 35, will engage the notch, 36, on the shank and thereby the roller, 19, will be held at such an elevation as will prevent it from contacting with the shiftable rail, 18.

A lever, 37, on the exterior of the down- 60 projecting pedestal has engagement with the spring-bolt, 35, and when the engineer moves this lever the said bolt may be disengaged from the notch, 36, on the roller-shank, and thereupon the spring, 30, will force the shank 65 and roller, 19, downward to a position where

the roller will ride up on the shiftable rail, 18. When the roller, 19, is raised by riding up on the inclined end of the shiftable rail, the rock-shaft, 33, will be partly turned and this will give a quarter turn to the plug-valve, 26, 70 which will result in venting the train-pipe and cause the air-brakes to be applied and stop the train.

The mechanical connection between the two signal arms, 2, and 3, on the post, 1; the 75 signal lever, 8, in the tower, and the shifting rail, 18, that causes the air-brakes to be applied will now be described.

A bell-crank lever, 38, is on the signal post below the rock-shaft, 15, being secured by a 80 pivot-bolt, 39; one end of the said bell-crank lever has a weight, 40, to counterbalance the weight of the danger signal arm, 2. A link-rod, 41, connects the lever-arm, 14, heretofore named, with the weighted end of the bell- 85 crank lever, 38.

The link-rod, 41, is shown in Fig. 3 and Fig. 2, and its location can also be seen where it is broken off in Fig. 1. The weight, 40, in Fig. 3 is shown in its down position, and signal arm, 2, in its up position. A link-rod, 42, connects between the said bell-crank lever, 38, and the shiftable rail, 18, as shown in Figs. 1 and 3. This link rod, 42, insures a correct co-operative movement between the 95 changing of positions of the signal arms, 2, and 3, and the shifting of the rail, 18.

Referring now to Fig. 3. As already stated the spiral spring, 9, is around the rod, 10, to which the operator's hand-lever, 8, is 100 attached. The spring, 9, will normally hold the signal-operating lever, 8, at the "danger" position, also the signal arm, 2, and the rail, 18, at the danger position.

Attached to the rod, 10, is a bell-crank lever, 43, near the floor of the tower which works or moves in a vertical plane. Another bell-crank lever, 44, is also movable in a vertical plane near the ground; a rod, 45, connects the said two bell-crank levers, 43, 110 and, 44.

A bell-crank lever, 46, has position in a horizontal plane even with the rod, 24, that is connected with the several bell-cranks, 22, which serve to shift the rail, 18. A rod, 47, 115 connects the bell-cranks, 44, and, 46. This completes a description of the connecting mechanism.

Having thus described my invention what I claim and desire to secure by Letters Patent is,—

1. In a railway signal the combination of two pivoted signal arms which are at a right angle with respect to each other; mechanism connecting said two arms so that only one of said arms will be displayed or exposed at the same time; a rail alongside the main-track rail and shiftable toward and away from said track-rail; a roller on the tender to traverse said shiftable rail and move a valve in the 125 130

train-pipe of the air-brake; a signal-operating lever, 8; a spring, 9, to normally keep the signal-operating lever at the "danger" position; and connections between said two signal arms, the said shiftable rail and the signal-operating lever, whereby the parts named will be at the "safety" position only when manually held by the operator.

2. In a railway signal, the combination of a signal post having two pivoted signal arms connected together; a shiftable rail alongside the main track for operating the air-brake of

a train; a signal-operating lever; a spring to keep the said lever thrown normally to the "danger" position, and mechanical connections between the pivoted signal arms, the said shiftable rail, and the operating lever. 15

In testimony whereof I affix my signature in presence of two witnesses.
